P. JOHNSON ET AL

UNBREAKABLE ANTIGLARE LENS

Filed Sept. 17, 1921

WITNESS: Fred W. Ely,

Peter Johnson,
George A. Gray
INVENTOR

BY *Victor J. Evans*

ATTORNEY

UNITED STATES PATENT OFFICE.

PETER JOHNSON AND GEORGE A. GRAY, OF ARLINGTON, NEW JERSEY.

UNBREAKABLE ANTIGLARE LENS.

Application filed September 17, 1921. Serial No. 501,268.

To all whom it may concern:

Be it known that we, PETER JOHNSON and GEORGE A. GRAY, citizens of the United States, residing at Arlington, in the county 5 of Hudson and State of New Jersey, have invented new and useful Improvements in Unbreakable Antiglare Lenses, of which the following is a specification.

This invention relates to improvements in 10 antiglare lenses and one of the principal objects of the invention is to produce an unbreakable device of this nature.

Another object is to produce an anti-glare lens from a single sheet of celluloid and having 15 a plurality of light baffles.

Another object is to produce a device of this nature which shall be simple of construction, cheap to manufacture and highly efficient for the purpose for which it is designed. 20

With these and other objects in view which will be more apparent as the description proceeds the invention consists in certain novel construction and arrangement of parts, the 25 essential features of which are hereinafter fully described, are particularly pointed out in the appended claims and are illustrated in the accompanying drawing in which:—

Figure 1, is a front elevation of my improved unbreakable anti-glare lens. 30

Figure 2, is a vertical sectional view of the same.

Like characters of reference refer to like parts in both views.

Referring to the drawing in detail, 10 represents the body portion of the lens, the same being made of celluloid of uniform thickness and being frosted or otherwise negatively finished. Formed out from the surface of 35 the member 10 are a plurality of curved hoods or shields 11, which are also frosted. Joining the lower edges of the elements 11,

with the body portion 10, and arranged at a slight angle are elements 12 which are made from clear celluloid so as to permit the easy 45 passage of the light from the source of illumination downwardly on to the road.

It will be seen in this manner we have produced an anti-glare lens for automobile and other headlights which is practically unbreakable and which effectually prevents direct projection of a heavy beam of light and which through the angular clear elements 12 further causes the light to be directed downwardly and forwardly on to the road where 55 it is needed.

While we have described what we deem to be the most desirable embodiment of our invention, it is obvious that the details may be changed without departing from the spirit 60 of our invention and we therefore do not limit ourselves to the precise details of embodiment described and illustrated but may resort to such changes as lie within the province of a skilled mechanic and the range of 65 equivalency.

What is claimed is:—

1. As a new article of manufacture, an anti-glare lens formed of a single piece of 70 frosted celluloid and comprising a body portion, and hoods integral therewith, said hoods having angularly disposed clear base elements.

2. A lens formed of frosted celluloid having superposed hoods projecting from one 75 face thereof and arranged in parallel relation with respect to each other and each provided with a clear angularly disposed portion at its bottom integral with the body 80 of the lens.

In testimony whereof we have affixed our signatures.

PETER JOHNSON.
GEORGE A. GRAY.
